INVENTOR
HERBERT T. BALLARD
BY HIS ATTORNEY
Harry Smith

UNITED STATES PATENT OFFICE.

HERBERT T. BALLARD, OF NORRISTOWN, PENNSYLVANIA.

NEEDLE CYLINDER FOR KNITTING MACHINES.

1,406,254.

Specification of Letters Patent. Patented Feb. 14, 1922.

Application filed June 18, 1921. Serial No. 478,579.

To all whom it may concern:

Be it known that I, HERBERT T. BALLARD, a citizen of Great Britain, residing in Norristown, Pennsylvania, have invented 5 certain Improvements in Needle Cylinders for Knitting Machines, of which the following is a specification.

My invention relates to needle cylinders for knitting machines and especially to that 10 type of cylinder which has an annular series of sinkers or web-holders secured thereto around the top, these sinkers alternating with the needles and consisting of steel bits set into radial grooves in the top of the 15 cylinder and being hooked so as to catch and retain the sinker wales of the knitted web as the needles rise.

The object of my invention is to so mount the sinkers upon the cylinder top that they 20 will be firmly and positively held in their predetermined positions but at the same time will be readily releasable so that a bent, broken or otherwise injured sinker may be quickly and easily removed. This 25 object I accomplish in the manner herein-after set forth, reference being had to the accompanying drawing, in which—

Fig. 1 is a vertical sectional view of a knitting machine needle cylinder equipped 30 with sinkers mounted in accordance with my invention;

Fig. 2 is a similar view of the cylinder and sinkers in disassociated relation, and

Fig. 3 is a similar view of a certain sleeve 35 and nut employed in connection with the cylinder and sinkers shown in Fig. 2.

Referring, in the first instance, to Fig. 1, I show a needle cylinder 1, threaded at 1^a at its lower end to screw into the bed plate 40 of a knitting machine, and equipped at its top with sinkers 2 which are retained in position by means of a sleeve 3 centrally disposed within the cylinder 1. For purposes of clarity and to avoid confusion in 45 the showing, only the two sinkers at diametrically opposite sides of the cylinder are illustrated in the drawing.

The upper end of the cylinder 1 is provided with a series of radial slots or grooves 50 4 (Fig. 2), each of which receives one of the sinkers 2 and provides side bearings therefor. Each sinker 2 is provided with a downwardly depending tail 2^a the rear face of which abuts against the inner face 55 5 of the top of the cylinder whereby radial bearing is provided for the sinkers. To in-

sure this radial bearing by forcing the sinkers radially outward, the inner face of each sinker is bevelled, as shown at 2^b, Fig. 2, and coöoperating with the bevelled faces of 60 the sinkers is the outer face of an outwardly flaring head 6, (Fig. 3) on the sleeve 3 which is disposed within the cylinder. Preferably, the inner face of the head 6 is bevelled as shown in Figs. 1 and 2, so that it 65 will not interfere with the free delivery of web from the needles. The lower end of the sleeve 3 projects downwardly below the bottom of the cylinder 1 and is threaded for the reception of a retaining nut 7. The 70 upper face of this nut bears against the lower face of the bottom of the cylinder and, as it is tightened upon the threaded lower end of the sleeve 3, serves not only to retain the sleeve in position but also im- 75 parts the necessary downward pull to it which results in the firm maintenance of the flaring head 6 against the bevelled inner faces of the sinkers. Thus the rigid mounting of the sinkers is insured. The lower 80 edge of the nut 7 is preferably provided with a pair of diametrically opposite notches, as shown, so that it may readily be engaged by a screw driver or equivalent tool, and thereby manipulated. 85

Should any of the sinkers become bent, broken or otherwise damaged, its replacement is but a simple matter. The nut 7 is unscrewed from the bottom of the sleeve 3 and the latter is removed, vertically. The 90 sinkers are thus exposed and any of them may be lifted from its place. To again assemble the parts it is merely necessary to lower the sleeve to position and replace its nut. 95

While my invention is designed especially for use in connection with needle cylinders of relatively small diameter and is particularly applicable to such use, it is not limited in this manner, as it can readily be adapted 100 for use with cylinders of larger size without departure from the spirit of my invention.

I claim:

1. The combination of a radially slotted 105 needle cylinder, sinkers set in the slots, said sinkers having bevelled inner faces, a sleeve disposed within said cylinder, a flaring head on said sleeve engaging the bevelled inner faces of the sinkers, and releasable means 110 for imparting downward pull to said sleeve.
2. The combination of a radially slotted

needle cylinder, sinkers set in the slots, said sinkers having bevelled inner faces, a sleeve disposed within said cylinder and having a threaded lower end projecting downwardly 5 beyond the bottom thereof, a flaring head on said sleeve engaging the bevelled inner faces of the sinkers, and a nut engaging the

threaded lower end of said sleeve and bearing against the lower face of the bottom of the cylinder.

10

In testimony whereof, I have signed my name to this specification.

HERBERT T. BALLARD.
